FIG. 2

FIG. 3

FIG. 1 is a perspective view of a tire showing my new design, it being understood that the tread pattern is repeated throughout the circumference of the tire, which is shown schematically by solid lines;

FIG. 2 is an enlarged fragmentary developmental plan view of the tread pattern; and

FIG. 3 is an enlarged sectional view taken along the line III—III in FIG. 1.

I claim:

The ornamental design for a tire, as shown and described.
